UNITED STATES PATENT OFFICE.

MILLER REESE HUTCHISON, OF WEST ORANGE, NEW JERSEY.

SIGNAL RECORDING AND TRANSCRIBING METHOD AND APPARATUS.

Application filed January 21, 1920, Serial No. 352,921. Renewed August 7, 1923.

To all whom it may concern:

Be it known that I, MILLER REESE HUTCHISON, a citizen of the United States, and resident of West Orange, in the county of Essex and State of New Jersey, have invented certain new and useful Improvements in Signal Recording and Transcribing Methods and Apparatus, of which the following is a specification.

10 My present invention relates more particularly to the recording and transcribing of wireless telegraph messages, although it may be usefully employed for other signals sent by other methods.

15 According to present day practice, it is common to have the wireless transmitting apparatus generate oscillations and radiate waves of high frequency, say 36,000 cycles per second. Such frequencies are above the 20 limit of practical audibility and it is common to have the waves generated intermittently in rapidly succeeding groups of wave trains. One means of doing this is to have a rotary electrode for the spark gap so 25 that discharge of the oscillatory circuit is precipitated at the desired rate, say 320 times per second. Each oscillatory discharge gives rise to a train of say 75 or 30 waves of the 36,000 frequency, so that each wave train lasts about two-thirds of the interval between discharges. These 35 trains following each other at the rate of 320 per second are translated in the receiving apparatus in such manner that they are heard as notes having a pitch of 320 per second, continuing a short time for the dots and a longer time for the dashes.

Wireless sending stations are now able 40 through improvements in the sending apparatus, to transmit at a rate much faster than the receiving operator can transcribe. Consequently, it has been proposed to record the notes constituting received signals, on a phonograph record, rotated at as high a 45 rate of speed as will permit of good recording, and then transcribe them from said record when rotating it in the reproducer at as low a speed, such as will give good reproduced sounds.

50 There is no particular difficulty in such phonographic recording. The incoming cir-

cuit that ordinarily connects with the head set of the operator is merely connected to a magnet which actuates the recording jewel of a cylinder phonograph which is revolving at a rate of say 125 revolutions per minute, thereby recording the intermittent 320 pitch note which represents the dots and dashes. Nor is there any great difficulty 55 in reproducing and transcribing from such 60 record at a considerably lower speed.

It has been found, however, that if the messages are sent at a very high rate say 100 words per minute, which is possible with the improved sending apparatus now 65 available, the speed of the reproducing phonograph would have to be reduced to say 30 revolutions per minute in order to reach the desired transcribing speed of 25 words per minute. The result is not satisfactory 70 because such reduction in speed reduces the pitch of the note to 80 vibrations per second with the result that the signal sounds as a gutteral grunt, easily confused with the inherent phonograph "scratches" 75 and with the noises due to "static" or "atmospheric" disturbances which are recorded with the signals.

In order to meet these conditions and to 80 enable the phonographic method of recording and transcribing to be practiced at such high rates of signaling as the sending station may be capable of transmitting, my invention 85 contemplates employing means at the receiving station to break up each of the received wave trains into much smaller lengths, so that the note in the receiving instrument will be of much higher pitch. This pitch will be proportioned to the speed 90 of sending and to the desired rate of transcribing so that, after recording at a speed not too high for good recording and after the pitch of the note has been reduced by the slow speed required for effective reproducing and transcribing, the note in the 95 reproducer will still be of a frequency giving good audibility, say two to three hundred per second. For instance, if 100 words per minute are being sent and if the operator can transcribe at 25 words per minute, 100 the interruptions may be such as to produce in the recorder, a note of say 1000 or

1500 per second, so that when reproduced at say one-quarter the recording speed the reproduced note will be of 250 or 375 pitch.

The above and other features of my invention may be more fully understood from the following description in connection with the accompanying drawings, in which

Figure 1 is a diagram with legends illustrating an application of my invention to a wireless transmitting and receiving system; and

Figure 2 is a similarly diagrammatic view of a phonograph reproducer.

In these drawings, the sending apparatus 15 comprises the generator G supplying currents through transformer T to an oscillatory circuit including condenser C, discharge device S and transformer T' through which it energizes the radiating conductor A. 20 These elements may be of any known or desired construction capable of energizing the sending wire with oscillations or waves of say the desired frequency, say 36,000 per second.

25 The rotor of the spark gap is driven at a speed which will precipitate oscillatory discharge and generate trains of 75 to 80 waves each, at a rate of say 320 trains per second.

A high speed transmitter capable of sending 30 at the rate of say 100 words per minute is diagrammatically indicated by stationary contact 1, and movable spring contact 2 operating to make and break the circuit of battery B at the required speed, by suitable means which in this case is diagrammatically indicated by the tape 4. This tape is perforated to correspond to the dots and dashes to be transmitted and spring 2 contacting through said perforations with stationary 35 contact causes corresponding make and break of the circuit of battery B. The resulting currents from battery B correspondingly energize magnet M to close and open relay switch R in the generator circuit.

40 The waves sent out by such a station can be utilized to produce sounds in the ordinary operator's receiving telephone and he can translate and write down the message in the usual way, provided the speed of sending is not too high. In such case sound representing the dots and dashes will be short notes and long notes respectively, and all will be of the same 320 pitch. My purpose, however, is to transmit at speeds too high for 45 intelligent receiving and transcribing by this ordinary method.

For my purposes, the receiving station may consist of any suitable receiving conductor A¹, energizing through a transformer T¹, a closed circuit through condenser C¹. The latter circuit, as also the receiving conductor A¹, will be tuned to the 36,000 frequency of the waves radiated from the sending station. The received waves are applied to a suitable wave responsive device D, in this

case indicated as an audion. The audion and its keep-alive battery B¹ are well known and need not be further described. The audion or other wave responsive device will operate in response to the received energy, 70 to cause and control the flow of corresponding pulsating currents, from battery B², through the audion and through the interposed electromagnet M¹.

As is well known, the effect of each wave 75 train received in such a system is to cause increased flow of current from the battery. Such wave trains will follow each other, and the corresponding battery impulses will energize magnet M¹, at the rate of 320 per 80 second. A relatively long succession of such magnetizations will produce a relatively long note indicating a dash and a relative short succession, will produce a shorter note indicating a dot.

85 In ordinary practice, the magnet M¹ would be the electromagnet of the operator's telephone receiver but for purposes of the present invention, said magnet is used to vibrate a phonograph diaphragm 6 provided 90 with cutting jewel 7 in contact with the wax cylinder 8, thereby recording on the cylinder the long and short notes representing the dashes and dots.

95 In such receiving system, I interpose an interrupter I adapted to break up the received signal elements into still shorter lengths, so as to produce a note of much higher frequency, say 1000 or 1500 per second. As shown in the drawings, the interrupter I is arranged to short circuit the secondary of transformer T², the primary of which is in shunt to condenser C² and in series with the circuit of battery B² and audion D. The rotor is driven at the required speed by any suitable means. Every time a projection 12 makes contact with terminal 13 the effect is similar to short circuiting the primary in the circuit of condenser C² and audion D. Thus the relatively 100 long fluctuations from the battery are broken up into shorter fluctuations of the desired higher pitch. If a record cylinder made by this method records at 125 revolutions per minute and is operated to reproduce at 30 revolutions per minute, only the 105 1000 or 1500 pitch note will be particularly noticeable.

110 An advantage of my invention is that the capacity of a station can be doubled or tripled thereby minimizing the number of stations likely to interfere with each other as well as saving the cost of additional plants, which for trans-Atlantic work, is 115 very great.

120 From the foregoing description in connection with the accompanying drawings, it will be evident that my preferred method involves breaking up the battery fluctuations at the receiving station, to produce in 125 130

the indicating instrument a note, the pitch of which is the same multiple of a good audible pitch, that the word-per-minute of the sending station is multiple of a practical transcribing rate.

Any known or desired means may be used for generating, transmitting and receiving the signal impulses; any desired means may be employed for sending the signals at the desired high words-per-minute rate; and any desired means may be employed for breaking up the battery fluctuations into the required shorter, higher-pitch fluctuations.

I claim:

In the art of signalling by electromagnetic waves, the method which consists in radiating trains of waves broken by and in accordance with the dots and dashes of the signal to be sent, said dots and dashes representing the signal being transmitted at a rate several times the rate at which they can

be transcribed by an operator at the receiving station; intercepting said waves at a receiving station and interrupting the received wave trains representing the dots and dashes to produce shorter signal elements corresponding to a note of predetermined pitch at least three times as high as required for phonographic reproduction; utilizing the thus broken wave trains to produce fluctuations in a battery current corresponding to long and short notes of a frequency equal to that of said breaks; utilizing said fluctuations to cut undulations in a phonograph record; and reproducing the long and short notes representing the dots and dashes, at speeds approximately one-third the recording speed.

Signed at New York city, in the county of New York and State of New York, this 20th day of January, A. D. 1920.

MILLER REESE HUTCHISON.
